(57) **CLAIM**

The ornamental design for a water gun, as shown and described.

DESCRIPTION

FIG. 1 is a front, top perspective view of a water gun, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled 9 in FIG. 1;

FIG. 10 is an enlarged view of the area labeled 10 in FIG. 1;

FIG. 11 is an enlarged view of the area labeled 11 in FIG. 2; and,

FIG. 12 is an enlarged view of the area labeled 12 in FIG. 2.

The dash-dash broken lines in the drawings depict portions of the water gun that form no part of the claimed design. The dash-dot-dash broken lines shown in FIGS. 1, 2, 9, 10, 11 and 12 are for the purpose of depicting the boundary line of the enlarged view and form no part of the claimed design.

1 Claim, 12 Drawing Sheets
